UNITED STATES PATENT OFFICE.

CHARLES KIESSIG, OF SAN DIEGO, CALIFORNIA.

COMBINATION RIFLE-SIGHT.

SPECIFICATION forming part of Letters Patent No. 766,447, dated August 2, 1904.

Application filed November 23, 1903. Serial No. 182,329. (No model.)

To all whom it may concern:

Be it known that I, CHARLES KIESSIG, a citizen of the United States, and a resident of San Diego, in the county of San Diego and State of California, have invented certain new and useful Improvements in Combination Rifle-Sights; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to gun-sights, and more particularly to those used on rifles; and it consists in the improved and effective construction hereinafter set forth.

The object of my invention is to produce a gun-sight which will give a clear vision and not a blurred one, as is now given by the sights in common use. This object I accomplish by substituting hard rubber in the place of metal in the rear open sight and also by such other devices and combination of devices as will be hereinafter clearly set forth, and particularly pointed out in the claims appended.

In order that my invention may be clearly understood and readily carried into effect, I will now proceed, aided by the accompanying drawings, fully to describe the same.

Referring to the drawings, Figure 1 is a top plan view of my improved combination rifle-sight. Fig. 2 is a side elevation of the same. Fig. 3 is a rear end elevation showing a globe-sight in a horizontal position. Fig. 4 designates a front elevation with the globe-sight raised to a vertical position and with the sight partially raised. Fig. 5 is a longitudinal section taken on a line $\alpha\alpha$ of Fig. 1.

Similar figures of reference indicate corresponding parts in the several views.

1 is a metal extension-plate suitably constructed with the front in a little higher plane than the rear end. 1^a is a longitudinal slot in same.

2 represents standards or guide-pins arranged on and forming component parts of the rear of the plate.

3 is a globe-sight acting on a pin-axle 3^a.4 is the metal frame of the sight, provided with lugs or projections 4^a, in which lugs the axle 3^a is seated. Said frame is also provided with pillars 4^b, forming component parts of 55 said frame and bored to fit over the standards or guide-pins 2.5 is a hard-rubber or gutta-percha open sight dovetailed or otherwise suitably fitted into the frame 4 between the pillars 4^b. 606 is a milled screw located in the side of one of the pillars 4^b and engaging with one of the guide-pins 2.7 is a base-plate provided with an upward projection or guide 7^a, adapted to fit and act 65 in the slot 1^a. Said base-plate 7 is dovetailed to the gun-barrel in the usual manner.8 is a set-screw in the projection 7^a and base-plate 7, adapted to secure the said base-plate at any desired point in the slot 1^a. 70

The use of gutta-percha or rubber has been found by experience to entirely eliminate blurs or blotches which appear when metal is used, the latter even when colored by smoking, bluing, or tempering being objectionable, owing to the presence of the blurs or blotches. This blur in the notch prevails when metal is used in all kinds of light or shadow, obstructing an accurate view of the front sight, not present when rubber or gutta-percha is employed, the latter being used in their natural colored state. 80

The mode of operating my improved gun-sight is as follows: When it is desired to use the open sight only, the globe-sight is turned 85 down, as shown in Fig. 1. When the globe-sight is needed, it can be raised to the position as shown in Fig. 4, with the hole therein on a direct line with the notch in the open sight. When desired to adjust the distance between the front and rear sights of the gun, loosen the set-screw 8 and shove the plate 1 along the guide 7^a until the desired distance is attained. Tighten the set-screw 8 and get the proper elevation for range by 95 raising the frame 4 on the guide-pins 2 and then lock said frame to pins 2 by means of milled screw 6. The rear sight is made adjustable longitudinally, for the reason that some users prefer the sight as near the eye as 100

possible, while others prefer it farther off, and as most gun-barrels have the slot already cut in them to receive the sight, the adjustability of the sight is a convenience for the shooter.

Of course in practice the globe-sight may be left off entirely, if so desired.

I have entered into a detailed description of the construction and relative arrangement of parts embraced in the present and preferred embodiment of my invention in order to impart a full, clear, and exact understanding of the same. I do not desire, however, to be understood as confining myself to such specific construction and arrangement of parts, as such changes or modifications may be made in practice as fairly fall within the scope of my claims.

Having thus described my invention, what I claim as new and useful, and desire to secure by Letters Patent, is—

1. In a gun-sight of the kind described the combination of a suitable extension-plate provided with a longitudinal slot in the front end thereof, standards or guide-pins at the rear end of said plate and forming component parts thereof, a sight-frame provided with suitable vertical pillars said pillars being centrally bored, backwardly-projecting lugs on said frame, a globe-sight pivoted between said lugs, a hard-rubber open sight fastened securely between the vertical pillars, a milled screw fitted in one of said pillars, a base-plate adapted to be fastened to the gun-barrel, an upwardly-projecting guide on said base-plate adapted to fit into the slot in the extension-plate, and a set-screw acting in said guide all as set forth.

2. In a rifle-sight the combination with a suitable base-plate provided with a suitable guide and set-screw, of an extension-plate, a slot in said extension-plate adapted to receive the said guide, standards or guide-pins at the rear of said extension-plate forming component parts thereof, a suitable sight-frame, slotted pillars on said frame adapted to fit over and act on the guide-pins, a hard-rubber or gutta-percha open sight fitted into said frame between the pillars thereof, and a milled screw seated in one of the pillars and engaging with one of the guide-pins, said milled screw adapted to clamp the frame and its parts on the guide-pins, all as set forth and described.

3. The combination with an extension-plate provided with a suitable rear sight, of a longitudinal slot in the front of the said extension-plate, a base-plate suitably fastened to the gun-barrel, an upwardly-projecting guide on the rear of said base-plate adapted to fit into the longitudinal slot in the extension-plate, and a set-screw seated in said guide and adapted to secure the position thereof in the said slot all as set forth and described.

4. In a gun-sight, the combination with a suitable base-plate and extension-plate, of a

vertically-adjustable sight-frame attached at the rear of the extension-plate, an open sight carried in said frame, backwardly-projecting lugs on said frame, and a globe-sight pivoted between said lugs, substantially as described.

5. In a gun-sight the combination with a suitable base-plate and extension therefor, of guide-pins located at the rear end of and forming component parts of the extension-plate, a rear-sight frame adapted to fit upon and act on said pins, and an open sight fitted into said frame, and means for rigidly securing said frame and its parts on the said guide-pins, all as set forth.

6. In a gun-sight the combination with a suitable base-plate and extension therefor, of guide-pins located at the rear end of and forming component parts of said extension-plate, a sight-frame adapted to fit upon and act on said guide-pins, an open sight carried in said frame, backwardly-projecting lugs on said frame, an axle seated in said lugs, a globe-sight adapted to act on said axle and be brought in register with said open sight, and means for rigidly securing the frame on the guide-pins, all as set forth.

7. The combination of a suitable extension-plate, guide-pins at the rear end thereof, a sight-frame, vertical pillars thereon, said pillars being bored and adapted to fit over and act on the guide-pins, an open sight carried by said frame, backwardly-projecting lugs on said frame, an axle seated in said lugs, a globe-sight acting on said axle and adapted to be swung into register with said open sight, means for securing the frame on the guide-pins, and a suitable base for the extension-plate, all as set forth.

8. The adjustable extension-plate 1, the longitudinal slot in the front end thereof, the guide-pins or standards 2 located at the rear end of the plate 1 and forming component parts thereof, a globe-sight 3, an axle 3^a, a sight-frame 4, backwardly-projecting lugs 4^a forming component parts of said frame and adapted to seat the axle 3^a, the bored vertical pillars 4^b forming component parts of the frame 4 and adapted to fit over the guide-pins 2, a hard-rubber or gutta-percha open sight fitted into the sight-frame 4 between the pillars 4^b, the milled screw 6 seated in one of the pillars 4^b and engaging with one of the guide-pins 2, the base-plate 7 adapted to be suitably attached to the gun-barrel, an upwardly-projecting guide 7^a forming a component part of the plate 7 and adapted to fit into and act in the slot 1^a, and a set-screw 8 seated in said guide and adapted to secure said guide at any desired point in said slot, all as set forth.

9. In a gun-sight the combination of a suitable adjustable extension-plate, guide-pins located at the rear end of and forming component parts of the extension-plate, a rear-sight frame adapted to fit upon and act on said pins, an open sight fitted into said frame, a longi-

tudinal slot in said extension-plate, a base-plate adapted to be fastened to the gun-barrel, an upwardly-projecting guide forming a component part of said base-plate, and a suitable 5 set-screw seated in said guide for the purpose as described.

In testimony whereof I have signed my name

to this specification in the presence of two subscribing witnesses.

CHARLES KIESSIG.
